PEARL EDGE ATTACHMENT FOR SEWING MACHINES

Gilbert Fowler, Bayonne, N. J.

Application June 26, 1937, Serial No. 150,468
Renewed September 9, 1939

1 Claim. (Cl. 112—160)

My present invention relates to sewing machines and more particularly to an improved attachment for sewing machines for producing pearl edges on fabrics.

5 My invention is particularly adapted as an attachment for ordinary sewing machines, and in which the main working portions are located beneath the base of the sewing machine and in which the parts which contact with the work to produce the pearl edging extend through a slot in the usual plate in the base of the machine and cooperates with the presser-foot of the machine, and operates in synchronism therewith to form the pearl edge on fabric being passed through the machine.

An advantage of my invention is that it constitutes an attachment to the ordinary sewing machine, and may be removed therefrom and attached thereto without in any way effecting the 20 operation of the sewing machine. The attachment is such that it may be quickly attached to or removed from a sewing machine, and the attachment is of such character that no particular skill is necessary to adjust the same with regard 25 to the working parts of the sewing machine.

As the main working portions of the attachment are located beneath the base of the sewing machine, the actual working portions of the machine itself are all that are ordinarily visible.

30 With my device in working position the top of the sewing machine is free of all mechanism which would tend to disarrange or soil the goods being worked upon, which is an advantage as obviously the working parts of any mechanical device should have lubrication thereon.

An object of my invention is an improved pearl edging attachment for sewing machines.

An object of my invention is a pearl edge attachment for sewing machines which is capable of 40 attachment to the under side of a base of a sewing machine.

An object of my invention is a pearl edge attachment for sewing machines which may be attached to the under side of the base of the 45 machine, and only the portion operating in conjunction with presser-foot of the sewing machine extends above the base of the sewing machine.

Other objects and novel features of the construction of the device will appear as the description of the invention progresses.

In the accompanying drawing:

Fig. 1 is a plan view of a portion of a base of a sewing machine to which my present invention has been applied.

Fig. 2 is a front elevation of the structure shown in Fig. 1.

Fig. 3 is a bottom plan view of Fig. 2.

Fig. 4 is a plan view of a piece of fabric having pearl edging thereon made by the device shown in Figs. 1, 2 and 3.

Referring to the drawing, 10 designates the base or bottom plate of lock-stitch sewing machine, and on the under face of the base 10 is an integral bearing 11 in which is rotatably mounted 10 the usual main drive shaft 12. The shaft 12 is driven from any suitable source of power (not shown) and carries on one end the bobbin casting 13 for holding the usual bobbin of thread.

The base bottom plate 10 is ordinarily provided 15 with an orifice closed by a plate 14, secured in position in any convenient manner, as by screws 15 and which plate is provided with a perforation 16 through which passes the needle. The plate 14 is also provided with a plurality of slots 20 17 through which extend the material feed (not shown) which cooperates with the presser-foot 18. As is usually, the presser-foot normally rests on the plate 14 when the machine is in operation. The presser-foot is adjustably mounted on a rod 25 19 by thumb screw 20, the rod being yieldably held in the usual head (not shown) of the sewing machine.

The above is the construction of the usual sewing machine to which my present invention may 30 be applied. I prefer to make my device in the form of an attachment which may be readily attached to or detached from the sewing machine. As the operating mechanism of my device is to move in synchronism with the needle (not shown) 35 and the bobbin holder 13, I prefer to attach the driving connection with my device directly to the main shaft 12 of the sewing machine and, therefore, have shown the driving mechanism as a worm 21 attached to the main drive shaft 12 of 40 the machine by the set screws 22, or in any other suitable manner.

In one embodiment of my invention, the attachment comprises a plate 23 having at one end thereof an arm 24 secured thereto in any convenient manner, as by screws or by riveting. In the arm 24 and plate 23, are aligned bearings in which is rotatably mounted a shaft 25. This shaft 25, between the plate 23 and arm 24 has secured thereto a cam 26 and worm wheel 27, the 50 worm wheel 27 meshing with and being driven by the worm 21 attached to the main shaft 12. The cam 26 is of a shape to produce the desired type of pearl edging on fabric to be operated upon.

The cam 26 imparts a reciprocating motion to 55

a bar 28. One end of the bar 28 is slidably mounted in a guide 29, secured to the plate 23, and the other end is provided with a fork 30 which is slidably mounted on a screw 31, attached 5 to the plate 23. The bar 28 is continuously urged toward the cam 26 by a spring 32, one end of which is attached at the point 33 to the bar 28, and the other to the point 34 on the arm 24. The end of the bar 28 which engages with 10 the cam 26 is preferably rounded as indicated by the reference numeral 35.

The reciprocating bar 28 carries the arm or member 36 and carries the same in such form as to have it readily removable therefrom, as by 15 the screws 37. This arm 36 has one end thereof extending upwardly through the elongated slot 38, formed in the removable plate 14. The upper end of the arm 36 which extends through the slot 38 is provided with a device by means of 20 which a pearl edge forming blade 39 may be removable and adjustable attached thereto, as by threading to receive a screw 40.

The pearl edge forming knife or blade 39 being attached to the upper end of the arm 36, and the 25 arm 36 being attached to the reciprocable bar 28, the blade 39 reciprocates transversely of the presser-foot 18 as shown in Figs. 1 and 2. The ordinary presser-foot may be employed by forming a slot therein, or the ordinary presser-foot 30 may be cut off on a transverse line through the hole 41 therein, and through which passes the sewing needle, and to the portion remaining, the portion which was cut off, or a similar portion may be attached by means of a spring 42, as 35 clearly shown in Figs. 1 and 2.

As the main drive shaft 18 rotates, the worm 21 rotates the worm wheel 27, and thus the cam 26, in synchronism with the reciprocating motion of the usual needle carried by the machine, 40 and also in synchronism with the bobbin holder 13. The reciprocating bar 28 is therefore moved to the left, as shown in Fig. 3, by the cam against the tension of the spring 32, and when the rounded end of such bar 28 rides over the top of the 45 cam 26, the spring 32 acts to return the bar 28 to its normal position. As is apparent, this produces a reciprocating motion of the pearl edging blade 39 transversely of the presser-foot 18 and at a point adjacent to the needle passing through 50 the hole 41 in such presser-foot. Therefore the material 44 being fed through the machine by the feeding device, which passes upwardly through the slots 37 in the blade 14 and moving in the direction of the arrow shown in Fig. 1, 55 will have a line of stitching 45 thereon and such stitching will be in a substantially straight line. The pearl edging blade 39, however, moving inwardly to the left as shown in Fig. 1, and transversely to the line of movement of the fabric 44, 60 the fabric 44 will be indented at spaced intervals, as indicated by the reference numeral 45, and the fabric is distorted to some degree at each indentation, and therefore the line of sewing 45

in the finished article will appear as a wavy line as shown in Fig. 1.

There may be, with my device, a binder or finishing cord placed on the edge of the fabric 44, simultaneously with the forming of the pearl 5 edging as indicated in Fig. 1.

Such a binding is shown in Fig. 4, where a section of fabric 47 has the pearl edging 48 formed therein and attached to the edging is the cord 49. Such cord 49 is attached to the bottom of 10 each indentation, as at the point 50, by the line of sewing 51, the portions of the cord 49 between each sewing or around the swell of the edging 48 being free.

To assist in feeding the fabric 44 or 47 15 through the machine, to have the pearl edging formed thereon, and particularly to assist in feeding the cord 49 I find it advantageous to groove the lower end of the presser-foot 18, as 20 shown by the reference numeral 52 in Fig. 2.

The machine, when my device is used, may be the ordinary sewing machine and therefore adapted to be utilized for a general line of work. My attachment permits this, and for example, where the work to be done in the machine will 25 not be disturbed because of the presence of the end of the member 26 extending upwardly through the slot 38 of the plate 14, all that is necessary to disconnect my device from the sewing machine is to remove the edging blade 39 by 30 removing the screw 40. If however, the type of work to be done on the machine would be interfered with by that portion of the arm 36 extending upwardly through the slot 38 in the plate 14, the arm 36 may be removed from the 35 machine. No other work is necessary and no mutilation of the machine is necessary other than the provision of threaded holes into which may be placed screws for holding the plate 23 carrying the mechanism above described. 40

Whereas, I have described my invention by reference to specific forms thereof, it will be understood that many changes and modifications may be made without departing from the spirit of the invention. 45

I claim:

In a pearl edging attachment for operating in association with a sewing machine for producing a pearl edge hem on fabric and the like, the combination of a base plate adapted to be mounted on the sewing machine, a reciprocable bar thereon, a cam rotatably mounted on the base plate, and adapted to positively move the reciprocable bar in one direction, resilient means for moving the reciprocable bar in the other 50 direction, a pearl edging blade carried by said bar and operating in association with the sewing mechanism to produce a pearl edge hem on fabric and the like, and means for mounting said attachment on the under side of the base of a 55 sewing machine and with the pearl edge blade above the base.

GILBERT FOWLER.
